(57) **CLAIM**

The ornamental design for a tea drip catcher, as shown and
described.

DESCRIPTION

FIG. 1 is a front elevational view of a tea drip catcher
showing my new design;

FIG. 2—is a left side elevational view thereof, the right side
being a mirror image.

FIG. 3—is a rear elevational view thereof.

FIG. 4—is a top plan view thereof; and,

FIG. 5—is a bottom plan view thereof.
